UNITED STATES PATENT OFFICE.

CARL JOSEPH, OF BAYONNE, NEW JERSEY.

FASTENER.

1,051,893.

Specification of Letters Patent.

Patented Feb. 4, 1913.

Application filed October 8, 1910. Serial No. 585,092.

To all whom it may concern:

Be it known that I, CARL JOSEPH, a citizen of the United States, residing at Bayonne, in the county of Hudson and State of New Jersey, have invented certain new and useful Improvements in Fasteners, of which the following is a specification.

This invention relates to fasteners and its novelty consists in the construction and 10 adaptation of the parts as will be more fully hereinafter pointed out.

The object of the invention is to produce an efficient fastener by the use of which objects may be securely held against surfaces 15 inaccessible from the rear, one requiring a minimum sized aperture for the insertion of the fastener and a minimum amount of material for its manufacture and one which may, if desired, be withdrawn after use.

20 So far as known to me the usual fastener of the class to which my invention relates comprises a single main bar, to which is hinged or otherwise secured a toggle bar adapted to fall by gravity into the space 25 back of the wall into which it is designed to be inserted. The main bars are usually threaded to receive nuts and the toggle bars are either hinged directly to such bars or to an intermediate member secured thereto. 30 In either case the aperture in the wall required for the insertion of the fastener is much greater in width than the diameter of the main bar and once having been inserted there is no way of withdrawing the fastener 35 from the wall.

In the drawings, Figure 1 is a top plan view of a fastener embodying my invention, and a vertical section through a wall into which it is to be inserted. Fig. 2 is a side 40 elevation of the fastener inserted in the wall showing the toggle bar partly rotated to position. Fig. 3 is a view similar to that shown in Fig. 2 showing the toggle bar completely rotated to position and an object 45 secured against the wall. Fig. 4 is a view similar to Fig. 2 showing the toggle bar partly rotated to withdraw the same from position. Fig. 5 is an edge view of the device, a part of the same being broken 50 through to show a concealed part. Fig. 6 is an enlarged section on the plane of the line 6-6 in Fig. 5. Fig. 7 is a section of one of the members of the main bar, and Fig. 8 is a perspective of the sundry parts non- 55 assembled.

In the drawings 10 is a wall of which 11

is the front and 12 is the rear, 11 being accessible and 12 being inaccessible. It is provided with an aperture 13 of approximately the diameter of the main bar of the 60 fastener to be described.

The fastener comprises a main bar made of two longitudinal members 20 and 21 and a toggle bar 22 of the same width and cross sectional area substantially as one of the 65 members 20, and secured to the other member 21 of the main bar by a transverse pivot 23. A cord, wire, or other filamentary connection 24 serves to join the bar 22 and member 20. Each of the members 20 and 70 21 are preferably made substantially alike and each consist of a substantially semi-cylindrical bar having one plane side 200, two substantially smooth lateral surfaces 201 and 202 and a rounded upper surface traversed by a series of oblique indentations 203 resembling in general outline the threads of a screw. They are not true screw threads because it is designed to roll these bars in continuous pieces of any desired length but 75 they approximate sufficiently to such threads in shape to engage with the internal threads of a nut 30 of suitable size, so that when the two members 20 and 21 are assembled as shown in Figs. 3 and 5, a nut will readily 80 engage both of them to hold them firmly together. So far as I am aware it is practically impossible to roll screw threads on rods of the nature required for the purpose stated. These rods with one plane surface and transverse oblique indentations on the opposite side are practical, readily made and serve the purpose just as well as a perfectly formed half screw would do. 85

In using the device, the parts are assembled as shown in Fig. 1, the two plane surfaces of the members 20 and 21 being in contact. Also if it is subsequently desired to withdraw the fastener, the connection 24 is secured to the toggle bar 22 and the member 20. The parts being assembled the bar 22 and the members 20 and 21 are inserted through the aperture 13 until the operator is reasonably certain that the inner end of the bar 22 has cleared the inner side 12 of 100 the wall 10. The member 21 and bar 22 hinged to it may be inserted and bar 22 hinged to it may be inserted without the member 20 but it is easier to manipulate them all together. After the parts have 105 reached the positions stated the bar 22 is allowed to fall by gravity into the position 110

shown in Fig. 3 or it is positively moved into such position by pushing forward the member 20 against it. If no connection 24 is used and gravity is to be depended upon, 5 it is obvious that the portion of the bar 22 below the pivot 23 must be larger than the portion above the pivot, but where gravity is not relied on, the relative sizes of these parts or the position of the pivot are immaterial. When the parts described have assumed the position shown in Fig. 3, the member 20 is preferably pushed forward against the edge of the bar 22 and the nut 30 is placed over the assembled members 20 10 and 21 and against the article as a bracket 40 designed to be secured against the wall 10.

When it is desired to withdraw the fastener, the nut 30 is first removed, then the member 20 is withdrawn gently from the aperture and the connection 24 pulling on the bar 22 causes the latter to be rotated on its pivot 23 and brings it in alignment with the member 20, when the entire device can 25 then readily be withdrawn through the aperture 13.

The parts of the device are very cheap to make. They are readily assembled, inserted and removed from a wall. They may be 30 used over and over again and they require in their use an aperture no wider than the combined width of the two members of the main bar.

What I claim as new is:—

- 35 1. A fastener, comprising a pair of separate semi-cylindrical rods longitudinally slidable upon each other, one of said rods terminating short of one end of the other, a toggle bar pivoted on the inner face of the projecting end of the other rod and capable of swinging into and out of alignment with the first rod, and means for securing the two rods together and against relative longitudinal sliding movement.
- 40 2. A fastener, comprising a pair of sepa-
- 45

rate semi-cylindrical rods longitudinally slidable upon each other, one of said rods terminating short of one end of the other, a toggle bar pivoted on the inner face of the projecting end of the other rod and capable 50 of swinging into and out of alignment with the first rod, a connection between the said first rod and toggle bar for effecting the swinging movement of the latter on the longitudinal movement of the former, and means for securing the two rods together and against relative longitudinal sliding movement.

3. A fastener, comprising a pair of separate semi-cylindrical rods longitudinally 60 slidable upon each other, one of said rods terminating short of one end of the other, a toggle bar pivoted on the inner face of the projecting end of the other rod and capable of swinging into and out of alignment with 65 the first rod, said rods having their outer faces provided with diagonal indentations forming screw threads, and a nut detachably threaded on the rods for securing the two rods together and against relative longitudinal movement.

4. A new article of manufacture, consisting of a substantially semi-cylindrical rod having oblique indentations on the central portion of its curved face, said indentations 75 terminating short of the side edges of the rod.

5. A new article of manufacture, consisting of a substantially semi-cylindrical rod having smooth lateral margins and oblique 80 indentations in its curved face, said indentations being gradually reduced in depth and terminating at the said smooth lateral margins.

In testimony whereof I have affixed my 85 signature in presence of two witnesses.

CARL JOSEPH.
